UNITED STATES PATENT OFFICE.

DAVID GREENHOOT, OF CINCINNATI, OHIO.

CUFF-HOLDER.

SPECIFICATION forming part of Letters Patent No. 330,692, dated November 17, 1885.

Application filed August 22, 1885. Serial No. 175,056. (No model.)

To all whom it may concern:

Be it known that I, DAVID GREENHOOT, a citizen of the United States, residing at Cincinnati, in the county of Hamilton and State of Ohio, have invented certain new and useful Improvements in Cuff-Supporters, of which the following is a full, clear, and exact description, reference being had to the accompanying drawings, forming part of this specification.

My invention relates to an improvement in cuff-supporters, and has for its object the provision of means for holding a cuff on the arm or wrist without attaching it to the shirt-sleeve or arm, so that it can be readily removed with the coat. A cuff attached to the shirt-sleeve is apt to sag against the hand on one side, and become soiled on that side. By my supporter it is held suspended around the wrist and supported by the coat-sleeve, which is sufficiently firm to hold the cuff independent of the hand or wrist, so that the cuff, when perfectly free from outside pressure, does not touch the hand or wrist at any point. Whenever the coat is removed temporarily, as for work at a desk or the like, the cuffs, when attached to the shirt-sleeve, must be unbuttoned separately and laid aside with care to avoid soiling. By my supporter they may be removed with the coat and remain safely attached to it within the sleeve until the coat is again put on.

Another object of my invention is to overcome the difficulty of attaching the cuff to the inside of the coat-sleeve without making it draw on the lining of the sleeve, and thereby disfigure the set of the coat-sleeve, or else show through the sleeve by creases or folds produced by the pressure against the cloth of the sleeve.

It consists in an annular band, so conforming in size and shape to the coat-sleeve as to fit within the same and be held in place by it without showing through the cloth, and provided with a suitable catch, by which the cuff may be attached to it at any desired point, so as to extend beyond the end of the sleeve to expose a part of the cuff.

In the accompanying drawings, Figure 1 is a sectional view of the supporter and cuff in

place in a coat-sleeve. Fig. 2 is a side elevation of the supporter, broken away to show the catch.

The same letters of reference are used to indicate identical parts in both the figures.

A is an ordinary coat-sleeve, which is smaller at the wrist than at the elbow, tapering in the usual manner. B is an annular band made of some light stiff material—such as paper board—which may be covered with silk, or ornamented, as desired, and lined with thin sheet-rubber as a protector from perspiration, though that is not necessary. The band B is wider at the top than at the bottom—that is, it tapers to correspond with the shape of the coat-sleeve—and its lower diameter is larger than the sleeve at the wrist or an inch above the wrist, so that the band cannot slip out of the lower end of the sleeve. At the same time it is made wide and tapering enough to so distribute the outward pressure against the sleeve that it does not make a crease or mark to show on the outside of the sleeve. It may be made round or slightly flattened, as preferred. Within the band B is fastened a catch for attaching the cuff.

In the drawings I have shown the preferred form of catch, though I do not limit myself to that particular form.

The catch D consists of a thin piece of metal formed in a double loop, the upper end passing over the band, as shown; or the end d may be inserted between the band and its cover, so that it is secured firmly and is out of sight. The lower loop, d', is made with sufficient tension or spring to hold the edge of the cuff securely when inserted as shown in the drawings.

The cuff may be pushed up so as to be entirely within the sleeve, or it may extend beyond as much as desired. The loop d' will hold it at any point.

The cuff C is held in place by the stiffness of the coat-sleeve, and does not sag against the hand or wrist. It may be drawn out at the lower end of the sleeve, or may be taken off with the coat. The cuff or band thus pressing equally from all sides against the sleeve does not drag or pull the lining at any one point and cause it to bag, nor does it

press sufficiently at any one point to cause a crease in the cloth to show on the outside of the sleeve.

Having thus fully described my invention,
5 I claim—

A cuff-supporter consisting of an annular band within the coat-sleeve, and larger than

the lower end of the sleeve, and provided with an adjustable catch for attaching the cuff, substantially as described.

DAVID GREENHOOT.
